DESIGN FOR A NOVELTY THERMOMETER

John Bancroft, Jr., Wilmington, Del.

Application September 4, 1936, Serial No. 64,726

Term of patent 7 years

To all whom it may concern:

Be it known that I, John Bancroft, Jr., a citizen of the United States, residing at Wilmington, in the county of New Castle and State of Delaware, have invented a new, original, and ornamental Design for Novelty Thermometers, of which the following is a specification, reference being had to the accompanying drawing, forming part thereof.

Figure 1 is a side elevation of a novelty thermometer embodying my invention; and

Figure 2 is a front elevation thereof.

The important feature of the design is the safety pin holder.

I claim:

The ornamental design for a novelty thermometer as shown and described.

JOHN BANCROFT, JR.
